(57) **ABSTRACT**

A money handling apparatus is arranged to receive items of currency and classify each into at least one class. Each class of currency items is stored and managed by the money handling apparatus in order to be able to extract the received items. In some implementations, the money handling apparatus is arranged to receive items of currency, store items of currency, receive at least one service media, and transport at least one stored currency item to a removable storage unit in a specified sequence or order.

HANDLING OF DIFFERENT CLASSES OF CURRENCY

CROSS REFERENCE TO RELATED APPLICATIONS

This application is a national phase filing under 35 U.S.C. §371 of International application number PCT/US2009/058007, filed Sep. 23, 2009, which claims priority from provisional application number 61/099,402 filed Sep. 23, 2008. The contents of the prior applications are incorporated herein by reference in their entirety.

FIELD OF DISCLOSURE

The disclosure relates to the handling of different classes of currency within a currency handling apparatus.

BACKGROUND

It is known to provide a machine to receive and dispense items of currency in response to user activity. In conventional automated teller machines, a banknote is received from a user, authenticated and stored within a cashbox. In other conventional ATMs, the machine is configured to temporarily store currency for later dispensing to a user as change in a transaction. In some conventional devices, the inserted currency may be stored in individual cashboxes or recycling containers according to denomination.

In each of the above examples inserted items deemed to be non-authentic or unable to be identified are typically returned to the user and considered to be "reject" items. In other conventional systems there may be a permanent storage container or cashbox in which all non-authentic and poor quality authentic inserted currency items are placed for later removal.

SUMMARY

The disclosure relates to a money handling apparatus arranged to transport and store various items.

In one aspect, a money handling apparatus is arranged to receive items of currency and classify each into at least one class. Each class of currency items is stored and managed by the money handling apparatus in order to be able to extract the received items. In some implementations, the money handling apparatus is arranged to receive items of currency, store items of currency, receive at least one service media, and transport at least one stored currency item to a removable storage unit in a specified sequence or order.

Other aspects of the invention, and various features and advantages, will be readily apparent from the detailed description, the accompanying drawings, and the claims.

BRIEF DESCRIPTION OF THE DRAWINGS

FIG. 1 illustrates an example of a money handling apparatus.

FIG. 2 illustrates items being dispensed from a currency storage unit including a first and second storage.

FIG. 3 illustrates items being received by the currency storage unit.

FIG. 4 illustrates items being dispensed from the currency storage unit.

FIG. 5 illustrates items being received by the currency storage unit.

FIG. 6 illustrates items being dispensed from the currency storage unit.

2

FIG. 7 illustrates items being received by the currency storage unit.

FIG. 8 illustrates items being dispensed from the currency storage unit.

FIG. 9 illustrates items being dispensed from the currency storage unit.

FIG. 10 illustrates items being received by the currency storage unit.

FIG. 11 illustrates items being dispensed from the currency storage unit.

FIG. 12 illustrates items being received by the currency storage unit.

FIG. 13 illustrates a service coupon being received by the currency storage unit.

FIG. 14 illustrates items being dispensed from the currency storage unit.

FIG. 15 illustrates a service coupon being dispensed from the currency storage unit.

FIG. 16 illustrates various classes of items having been arranged within the removable storage cassette in a predetermined sequence.

FIG. 17 illustrates a money handling apparatus including a removable loader.

FIG. 18 illustrates a money handling apparatus including a control unit.

FIG. 19 illustrates a money handling apparatus including an external component.

FIG. 20 illustrates a money handling apparatus including a communications unit.

FIG. 21 illustrates an example of a money handling apparatus.

DETAILED DESCRIPTION

As illustrated in FIG. 1, a money handling unit 10 is configured to receive items of currency (e.g., banknotes) from a user, an authorized individual, or a removable loading unit.

In the example of FIG. 1, the money handling unit 10 includes a currency inlet/out 20 for receiving banknote(s), an authentication unit 30 for authenticating banknotes, a transportation mechanism 40 for transporting banknotes to and from various components within the money handling machine 10, and multiple currency storage units 50 coupled to transportation mechanism 40 and arranged for receiving and dispensing items of currency. In some implementations, money handling unit 10 further includes a cashbox 60 for receiving and storing items of currency from transportation mechanism 40, and a loading unit 70 for providing at least one item of currency to the money handling unit 10 for use as change in a transaction.

Inlet/outlet 20 is coupled to transportation mechanism 40 such that banknotes inserted into inlet/outlet 20 are received by the transportation mechanism 40. Typically, inlet/outlet 20 is configured to accept a wide variety of banknotes having various widths. In some implementations, a banknote presence sensing system 23 is coupled to inlet/outlet 20 and configured for sensing the presence of the banknote(s) in the inlet/outlet opening.

Authentication unit 30 is coupled to transportation mechanism 40 and is arranged to validate and classify items of currency, for example, according to known techniques. In some implementations, authentication unit 30 uses an optical sensing unit to discriminate an item of currency (e.g., to discriminate between genuine vs. non-genuine items, or to classify the items) and determine other characteristics of the document (e.g., condition, degree of soiling, rips, tears, holes, etc.). The optical sensing unit can be of any type (e.g., spectral

reflection and/transmission). Alternatively, the sensing unit can be any other type of currency sensing system (e.g., magnetic sensing, physical sensing). Authentication unit **30** can be configured to sense and discriminate items of currency or it can be arranged to provide sensed data to a control unit **100** for further processing.

Transportation mechanism **40** operatively couples inlet/outlet **20** to the authentication unit **30**. Transportation mechanism **40** includes a series of belts driven by an actuator to cause banknotes to move in an inward and outward direction relative to the entry and exit of the money handling unit **10**. In some implementations, transportation mechanism **40** includes one continuous transportation path arranged to move in forward or backward motion (or capable of moving in both the forward and backward directions). In other implementations, transportation mechanism **40** is comprised of a series of smaller transportation units to create a continuous transportation path. Other types of transportation mechanisms can be adapted for use within the money handling unit **10**. Transportation mechanism **40** is further coupled to currency storage units **50** for transporting banknotes (i.e., items of currency) to and from the storage units based on the desired operation of money handling unit **10**.

A currency storage unit **50** is mounted to money handling unit **10** and operatively coupled to transportation mechanism **40** for receiving and dispensing banknotes. In some implementations, currency storage unit **50** is removably mounted to money handling unit **10**. Currency storage unit **50** is arranged to store banknotes sequentially on a storage drum **55** (i.e., two-way storage). In some implementations, currency storage unit **50** is arranged to store banknotes in a stacked (i.e., face to face) manner. Banknotes selected to be stored within storage unit **50** are received from transportation mechanism **40** for later user as change in a transaction. Banknotes stored within currency storage unit **50** can be dispensed therefrom to transportation mechanism **40** for further processing by money handling unit **10**.

Money handling unit **10** further includes a control unit **100** for controlling the overall operation of the money handling unit. Control unit **100** includes a microprocessor **110** and memory **120** for processing and storing instructions to operate money handling unit **10**. Control unit **100** is arranged to determine how each inserted banknote is handled (e.g., where it should be stored or whether it should be returned to the user), and for controlling any component (e.g., components **30, 40, 50, 60, 70**) coupled thereto to accomplish movement of banknotes into, through and out of money handling unit **10**.

In some implementations, control unit **100** includes an external access for communicating with an external component **200** (e.g., handheld service tool or remote computer). In other implementations, money handling unit **10** includes a communications unit **300** for communicating with remote devices for receiving updates and/or service information.

Cashbox **60** is removably mounted to money handling unit **10** and is arranged to receive banknotes from transportation mechanism **40**. Cashbox **60** is configured to store banknotes identified by the money handling unit to be held within cashbox **60** for later removal by an authorized individual. Cashbox **60** is configured as a one-way storage device for currency items such that items contained in the cashbox cannot be extracted by money handling unit **10** and thus have to be removed from the cashbox when it is external to the money handling unit.

Loading unit **70** is removably mounted to money handling unit **10** and operatively coupled to transportation mechanism **40**. Loading unit **70** is arranged to have banknotes inserted therein at a location (e.g., banking center) remote from money

handling unit **10**. Loading unit **70** is configured to house either a single class of banknote (e.g., 5 euro) or multiple classes of banknotes (e.g., 5 euro, 10 euro, 20 euro) and supply its contents to money handling unit **10**. Once loading unit **70** is inserted into money handling unit **10** by an authorized individual, control unit **100** can instruct loading unit and transportation mechanism **40** to extract the contents of the loading unit. Each banknote dispensed from loading unit **70** is transported to authentication unit **30** to verify at least one of its validity, class or condition. Based on the results obtained from authentication unit **30**, money handling unit **10** sends each banknote to a respective storage unit.

In some implementations, money handling unit **10** has separate openings for receiving and dispensing items of currency. For example, a currency inlet **21** is for receiving at least one item of currency from a user and currency outlet **22** is for dispensing at least one item of currency to a user.

In some implementations, inlet **21** and/or outlet **22** are arranged to handle a bundle of banknotes at one time. More specifically, a user may provide a stack of banknotes to money handling unit **10** via currency inlet **21**. The stack of currency can be received by unit **10** where each banknote is feed by transportation mechanism **40** to authentication unit **30** one at a time.

Each banknote inserted through inlet **21** is fed to authentication unit **30** to determine at least one of its validity, class or condition. Each banknote inspected by authentication unit **30** is transported by transportation mechanism **40** to a respective two-way storage unit **50**. In some implementations, each two-way storage unit **50** contains two individual currency recycling drums **55**. Each recycling drum **55** is configured to store and dispense banknotes sequentially. In some implementations each recycling drum **55** is arranged to store a single class of banknote (e.g., 5 euro banknotes). However, in some cases, the drums are arranged to store a mix of banknote classes (e.g., 5 euro and 20 euro banknotes).

In some implementations, money handling unit **10** is configured to include multiple storage units **50**. Each storage unit **50** can be configured to store a different class (e.g., denomination or characterization) of currency. In implementations in which each storage unit **50** includes more than one storage drum **55**, each storage drum can be configured to store a specific class of currency as instructed by money handling unit **10**.

In operation, a user inserts at least one item of currency (e.g., banknote) into inlet **22**. As the banknote moves into inlet **22**, sensing system **23** senses the presence of a banknote thereby initiating transportation mechanism **40** to feed the banknote (and any subsequent banknotes, for example from a bundle) to authentication unit **30**. Sensed data obtained from authentication unit **30** allows for classification of each banknote into one of multiple classes based on the programmed operation of money handling unit **10**. For example, money handling unit **10** can classify an inserted item of currency as a valid banknote of a known denomination (e.g., 5 euro), a valid banknote of a known denomination in poor condition (e.g., not fit for circulation), a suspected counterfeit banknote (i.e., a copy), not a banknote, or a soiled or damaged banknote. Money handling unit **10** is configured to store or reject each item of currency class based on instructions stored within control unit **100**.

Once an individual banknote is classified by money handling unit **10**, it is transported by transportation mechanism **40** to the respective currency storage unit **50** for that class. Once all the inserted banknotes from the user have been identified by authentication unit **30**, and transported to their respective currency storage units **50**, money handling unit **10**

will return inserted items not selected for storage within the money handling unit **10** to the user through outlet **22**. If there is more than one item to be returned to the user that is not a valid item of currency, money handling unit **10** can be arranged so that the currency items are returned either in a bundle or in sequential fashion through outlet **22**.

In some implementations, change may need to be given for a transaction being conducted with the user. In that case, money handling unit **10** will dispense the appropriate combination of banknotes to the user based on instructions from control unit **100**.

In some implementations, there is a specific currency storage unit **50** for storing at least one of the inserted items classified as suspected counterfeit banknotes, suspect banknotes not clearly identified, and reject items. In this example, a currency storage unit **50** (e.g., having two storage drums **55**) manages the receipt of suspect banknotes (i.e., both counterfeit and not clear identifiable) and rejected items. A first drum **55a** is designated for storing suspect banknotes and a second drum **55b** is designated for storing reject items. As inserted items of currency are processed by money handling unit **10**, each item is transported to a respective storage unit **50** as instructed by control unit **100**.

FIG. 21 shows a simplified example for purposes of illustration. Money handling device **500** includes an inlet **521** for receiving at least one banknote from a user, an authentication unit **530**, a two-way storage unit **550** (including a first storage drum **555a** and second storage drum **555b**) for storing inserted items of currency, a single path transportation unit **540** for transporting inserted notes to and from storage unit **550**, and an outlet **522** for dispensing items of currency to the user. For simplicity, the operation of the illustrated device **500** is described using a single currency denomination (e.g., 5 euro), although the disclosure is not limited to such a configuration (see FIGS. 2 thru 11).

In operation, a user inserts, for example, a bundle of twenty 5-euro documents at inlet **521**. Transportation mechanism **540** feeds each of the twenty 5-euro banknotes from inlet **521** sequentially, one at a time, to authentication unit **530**. Authentication unit **530** senses each banknote and classifies it into one of the following classes:

TABLE 1

banknote classes (for the example of FIG. 21):

- 1) Valid 5-Euro fit for circulation
- 2) Valid 5-Euro unfit for circulation
- 3) Not a 5-Euro banknote
- 4) Suspected counterfeit 5-Euro banknote
- 5) Soiled or damaged 5-Euro banknote

In the foregoing example, the classes listed in Table 1 can be split further into two main groups. Group A includes item 1 from Table 1, and Group B includes items 2 thru 5 from Table 1. With respect to the money handling device **500** (FIG. 21), Group A items are stored on first drum **555a** and Group B items are stored on drum **555b**. To further explain the example, it is assumed that the results from authentication unit **530** for each of the 20 banknotes inserted by the user are characterized as shown in Table 2.

TABLE 2

Sample classification of the twenty banknotes:

1	CLASS 1
2	CLASS 1

TABLE 2-continued

Sample classification of the twenty banknotes:	
5	3 CLASS 1
	4 CLASS 1
	5 CLASS 3
	6 CLASS 1
	7 CLASS 1
	8 CLASS 1
	9 CLASS 1
	10 CLASS 4
	11 CLASS 1
	12 CLASS 1
	13 CLASS 1
	14 CLASS 1
	15 CLASS 2
	16 CLASS 1
	17 CLASS 1
	18 CLASS 1
	19 CLASS 1
	20 CLASS 5

20 Based on the classification for each of the twenty banknotes listed in Table 2, the following banknotes are stored on first drum **555a**: notes 1-4, 6-9, 11-14 and 16-19. Additionally, the following banknotes are stored on second drum **555b**: notes 5, 10, 15 and 20.

25 In some implementations, inserted items classified as CLASS 3 items are to be returned to the user. In the current example implementation, the first item stored on drum **555b** is a CLASS 3 item and, therefore, must be returned to the user. In order to accomplish this, the three other notes stored on drum **555b** (for example) must be moved off drum **555b** so that the CLASS 3 note can be received by transportation mechanism **540** and thus returned to the user via outlet **522**. In the current example, this can be accomplished by reversing drum **555b** in a direction opposite that used for receiving items so that the first note available to be dispensed (i.e., the CLASS 5 note) can be sent to transportation mechanism **540**. Once this note is received by transportation mechanism **540**, it is transferred temporarily to first drum **555a**. Each of the 30 notes on drum **555b** that is to be separated from CLASS 1 notes, and that is not a CLASS 3 note, can be stored temporarily on drum **555a** so that the CLASS 3 note(s) can be dispensed from drum **555b** to transportation mechanism **540** and thus returned to the user via outlet **522**. Once the CLASS 45 3 note is dispensed from second drum **555b**, any notes stored temporarily on first drum **555a** can be returned to second drum **555b** via transportation mechanism **540**. The foregoing is simply an example of a particular implementation. Other examples are within the scope of the disclosure.

50 Money handling unit **10** can be arranged with additional currency storage units **50** such that each class of currency items listed in Table 1 is stored within a dedicated currency storage unit **50**. Also, each class of currency items listed in Table 1 can be stored in a dedicated storage drum **55** within a 55 respective currency storage unit **50**.

55 In some implementations, money handling unit **10** is arranged to store acceptance or characterization information for various items of currency. For example, for each item of currency in which money handling unit **10** is configured to accept, a sensing profile (e.g., spectral response, magnetic response) complimentary to the type of sensing unit employed can be used to classify and inserted item according to known techniques.

60 In some implementations, there are specific coupons or separating cards that can be accepted by money handling unit **10** so that the money handling unit **10** operates in a specified manner. Specifically, an authorized person (e.g., service

operator) can insert unique an operator card or coupon into money handling unit **10** to cause a complementary class of currency items to be transported and deposited into cashbox **60**. Under certain conditions, a service person may need to extract currency items stored within money handling unit **10**. To accomplish this, the service person would insert a unique service coupon to request money handling unit **10** to deposit the corresponding currency item into cashbox **60**. For example, there can be a unique service card for each class, or any identified class recognized by money handling unit **10**.

The operation for extracting at least one class of currency from money handling apparatus **10** is now described. A service person requiring the removal of at least one class of currency items stored within money handling unit **10** inserts one or more corresponding coupons (or service tickets) that cause the money handling unit to deposit sequentially all currency items of that class corresponding to the inserted coupon into cashbox **60**. If it is desired to have any additional classes of currency items transferred to cashbox **60**, the service person instructs money handling unit **10** to have the next desired class of currency to be deposited sequentially in cashbox **60**. In various implementations, the service person can interact with money handling unit **10** directly or remotely. In some implementations, the service person interacts with money handling unit **10** via service media (e.g., a service coupon, a connected handheld device, a wireless communication device or a computer). The operation of inserting a service coupon into money handling unit **10** can be repeated as many times as necessary, depending on whether there are different classes of currency items required to be removed from the money handling unit.

By way of example, money handling device **500** includes a currency storage unit **50** having first and second drums **555a** and **555b**, and a cashbox **560** as described in the previous example. The service operator inserts service coupon **700** corresponding to CLASS 1 currency items. Upon inserting service coupon **700** into inlet **521**, transportation mechanism **40** is actuated to transport the service coupon to authentication unit **530**. Authentication unit **530** recognizes (e.g., via spectral response) the inserted item as service coupon **700**, enabling money handling device **500** to execute operational instructions to have all CLASS 1 currency items dispensed to cashbox **560** via transportation mechanism **540**. In order to transfer all CLASS 1 documents to cashbox **560**, service coupon **700** is stored temporarily on storage drum **555b** (i.e., where CLASS 1 currency items are not stored). Once service coupon **700** is stored temporarily on storage drum **555b**, the money handling device operates to cause CLASS 1 currency items to be dispensed from storage drum **555a** to cashbox **560** via transportation mechanism **540**. Once all CLASS 1 currency items have been transferred to cashbox **560**, service coupon **700** is dispensed from storage drum **555b** to cashbox **560** via transportation mechanism **540**.

If it is desired to have CLASS 2 currency items transferred into cashbox **560**, the service person inserts a service coupon **800** corresponding to CLASS 2 currency items into money handling device **500**. Once service coupon **800** is inserted into inlet **521**, transportation mechanism **540** transports the service coupon to authentication unit **530**. Authentication unit **530** recognizes (e.g., via spectral response) the inserted item as service coupon **800**, enabling money handling device **500** to execute operational instructions to have all CLASS 2 currency items dispensed to cashbox **560** via transportation mechanism **540**. In order to transfer all CLASS 2 documents to cashbox **560**, service coupon **800** is stored temporarily on storage drum **555a** (i.e., where CLASS 2 currency items are not stored).

Once service coupon **800** is stored temporarily on storage drum **555a**, the money handling device operates to cause CLASS 2 currency items to be dispensed from storage drum **555b** to cashbox **560** via transportation mechanism **540**. In the previous example of twenty banknotes (see Table 2), there is more than one class of currency items stored on storage drum **555b**. Any currency items residing on drum **555b** must be moved temporarily from drum **555b** to allow the CLASS 2 currency item to be dispensed from storage drum **555b** to cashbox **560** via transportation mechanism **540**. In the current example, the CLASS 3 and CLASS 4 currency items are transferred temporarily from storage drum **555b** to storage drum **555a** as previously described. Once all CLASS 2 currency items have been transferred to cashbox **560**, the CLASS 3 and CLASS 4 currency items stored temporarily on storage drum **555a** are returned to storage drum **555b**, thus allowing service coupon **800** to be dispensed from storage drum **555a** to cashbox **560** via transportation mechanism **540**. The foregoing sequence of operations can be repeated as necessary for each additional service media received by the device **500** from the service person to have the corresponding currency items transferred to cashbox **560**. FIG. 16 shows the result of a service person inserting the following service coupons into money handling device **500**.

TABLE 3

Example: Service Coupons inserted to stack currency items in cashbox in FIG. 16
Service Coupon 700 - CLASS 1 currency items
Service Coupon 800 - CLASS 2 currency items
Service Coupon 900 - CLASS 3 currency items
Service Coupon 1000 - CLASS 4 currency items
Service Coupon 1100 - CLASS 5 currency items

In an example, multiple service coupons (or identifiable media) recognizable by money handling unit **10** are inserted therein to cause the transfer of corresponding currency items to be received by cashbox **60** in a sequential manner. In some implementations each inserted currency class is separated within cashbox **60** via the corresponding service coupon as shown in FIG. 16. In some implementations, all service coupons (e.g., **700, 800, 900, 1000, 1100**) can be inserted into money handling unit **10** at the same time. Inserting a bundle of service coupons into money handling unit **10** facilitates transferring all corresponding currency items to cashbox **560** according to a predetermined sequence.

A particular service coupon can, in some cases, correspond to more than one currency class based on the desired operation and configuration of money handling unit **10**. Specifically, money handling unit **10** can be arranged to receive a single service media (e.g., service coupon or instruction from an external component) whereby the money handling unit transports one or more stored currency items to cashbox **60** in a predetermined order or sequence.

In some implementations, an external component (e.g., a remote service center) can communicate with money handling unit **10** via a wireless or other network to provide a service media (e.g., storing operational instructions) to cause currency items stored in the unit to be transported to cashbox **60** in a predetermined sequence. In some implementations, control unit **100** is arranged to monitor and store in memory **120** at least the position and classification of each item of currency stored within money handling unit **10**. Money handling unit **10** can be configured such that the contents and relative position of items stored within cashbox **60** are communicated to an external component **200**. In some implemen-

tations, cashbox 60 contains a memory unit for receiving (from money handling unit 10) data corresponding to the cashbox contents and for storing the data in the memory unit.

Other implementations are within the scope of the claims.
What is claimed is:

1. A money handling apparatus for dispensing items of currency and accepting at least one service media comprising:

an authentication unit to classify received items of currency;

at least one first storage unit coupled to the money handling apparatus to dispense items of received currency;

a transportation mechanism to transport items of received currency to and from the at least one first storage unit;

a removable storage unit to receive at least one item of received currency stored in the at least one first storage unit;

the authentication unit having a mechanism for recognizing the at least one service media presented to the money handling apparatus as corresponding to a particular class of currency items capable of being stored by the at least one first storage unit; and,

the transportation mechanism structured and arranged to transfer at least one item of currency, when present in the at least one first storage unit, to the removable storage unit when the item of currency belongs to the particular class corresponding to the at least one service media.

2. The money handling apparatus according to claim 1 wherein the at least one storage unit comprises a storage drum.

3. The money handling apparatus according to claim 1 wherein the at least one storage unit comprising at least two storage drums.

4. The money handling apparatus according to claim 3 wherein the at least two storage drums are configured to store different quantities of currency items.

5. The money handling apparatus according to claim 1 further comprising a control unit to control operation of the money handling apparatus.

6. The money handling apparatus according to claim 5 wherein the control unit is arranged to store characterization information for at least one class of currency item.

7. The money handling apparatus according to claim 5 wherein the control unit is arranged to store characterization information for at least one service media.

10 8. The money handling unit according to claim 5 wherein the control unit is arranged to recognize at least one service media.

9. The money handling unit according to claim 8 wherein the service media is a coupon received by the authentication unit.

10. The money handling apparatus according to claim 9 wherein the authentication unit is arranged to characterize at least one service media.

20 11. The money handling apparatus according to claim 1 further comprising a communications unit.

12. The money handling apparatus according to claim 11 wherein the communications unit is arranged for wireless communication with a component external to the money handling apparatus.

13. The money handling apparatus according to claim 12 arranged to receive a service media via a wireless communication from a remote network.

30 14. The money handling apparatus according to claim 1 wherein the service media is a coupon inserted into the money handling apparatus.

15. The money handling apparatus according to claim 11 wherein the service media is received by the communications unit from an external component.
